COMBINED MASTER TUNING FORK, RESONATOR SUPPORT AND STRIKER OR SIMILAR ARTICLE

Robert H. Peirce, 1212 Navlet Court,
Sunnyvale, Calif. 94087

Filed Apr. 13, 1971, Ser. No. 133,778

Term of patent 3½ years

Int. Cl. D17—04

U.S. Cl. D56—1 E

FIG. 1

FIG. 2

FIG. 4

FIG. 3

FIG. 1 is a top perspective view of a combined master tuning fork, resonator support and striker or similar article, showing my new design;

FIG. 2 is a side elevational view, the opposite side being substantially a mirror image thereof;

FIG. 3 is a side elevational view as seen from the right in FIG. 2; and

FIG. 4 is a top plan view thereof.

I claim:

The ornamental design for a combined master tuning

fork, resonator support and striker or similar article, as shown and described.
